UNITED STATES PATENT OFFICE.

ERNEST WÜSTNER, OF PHILADELPHIA, PENNSYLVANIA, ASSIGNOR TO
GLOBE JACK COMPANY, OF PHILADELPHIA, PENNSYLVANIA.

LIFTING-JACK.

SPECIFICATION forming part of Letters Patent No. 786,706, dated April 4, 1905.

Application filed October 20, 1904. Serial No. 229,291.

To all whom it may concern:

Be it known that I, ERNEST WÜSTNER, a citizen of the United States, residing at Philadelphia, in the county of Philadelphia and State of Pennsylvania, have invented certain new and useful Improvements in Lifting-Jacks; and I do declare the following to be a full, clear, and exact description of the invention, such as will enable others skilled in the art to which it appertains to make and use the same.

My invention is an improved lifting-jack; and it consists in the construction, combination, and arrangement of devices hereinafter described and claimed.

One object of my invention is to effect improvements in the construction of the worm-gear which meshes with the rack-teeth of the vertically-movable bar.

A further object of my invention is to effect improvements in the construction of the standard which carries the vertically-movable rack-bar and which forms a casing to inclose the worm-gear and provides bearings for the journals thereof.

A further object of my invention is to effect improvements in the means for rotating the worm-gear by a step-by-step movement in either direction to raise or lower the vertically-movable bar.

In the accompanying drawings, Figure 1 is a vertical central sectional view of a lifting-jack embodying my improvements, the vertically-movable bar being shown in elevation and the worm-gear being shown in section.

Fig. 2 is a transverse sectional view of the same, taken on the plane indicated by the line *a a* of Fig. 1 and omitting the lever. Fig. 3 is a detail view showing a portion of the toothed face of the vertically-movable bar in elevation and the volute or worm flange of the gear which engages the said toothed bar, in section, and Fig. 4 is a plan view of the face of the worm-gear.

The standard 1 of my improved lifting-jack is made of a pair of separable sections 2, each of which is a single casting, and comprises a shank portion 3, having a groove 4 on its inner side, a foot portion 5, and a semi-circular casing portion 6 on one side near its

upper end, the said semicircular casing portion being laterally inclined and lying obliquely with reference to the shank, the upper side of the interior portion of the casing merging into and communicating with the groove 4. One flange, 7, of each standard section is formed at its lower end with a web 8, which extends outward nearly to one end of the foot, the said flange being also formed with a web portion 9, which extends to the lower inner side of the semicircular casing portion 6. The opposite flange, 10, of each section has a vertical opening 11, which extends for a suitable distance from its lower end to form a clearance-slot, in which the lower lift 12 of the vertically-movable bar 13 operates, as hereinafter described. The said flange 10 is formed at its lower end with a reinforcing-web 14. Between the opposing sides of the said webs 14 of the respective sections is formed an opening 15, which communicates with the lower end of the guide-slot formed by the openings 11 and enables the lower lift 12 to lie therein when the vertically-movable bar is at the lowest limit of its movement. The said sections of the standard are secured together by bolts, rivets, or other suitable devices, as at 16.

The vertically-movable lift-bar is provided on its front side with rack-teeth 17, each of which is curved from end to end, as shown in Fig. 3. The said vertically-movable bar is formed at its upper end with a head 18, recessed on its upper side, as at 19, to adapt it to fit against the under side of an axle or other object.

In the circular casing of the standard is mounted a worm-gear 20. Said worm-gear has a frusto-conical inner face 21, on which is a volute or worm flange 22, which is flared outwardly, so that its outer face 23 is substantially perpendicular to the conical inner face of the gear. The radius of this volute or worm flange is substantially equal to that of the inner or lower faces of the teeth of the vertically-movable bar, and the construction of the outer face 23 of the volute or worm flange, which is substantially perpendicular to the conical face of the gear, adapts the

- outer side of the said volute or worm flange to lie parallel with and snugly engage the under opposing sides of the teeth of the rack or vertically-movable bar in succession as the 5 bar is raised or lowered by the rotation of the said worm-gear. The latter is formed or provided on its inner side at its center with a journal 25, which engages a bearing 26, that is formed at the inner sides of the members of 10 the circular casing in which the worm-gear is mounted, and the latter is formed or provided on its outer side with a journal 27, which turns in a bearing 28, which is formed in the outer sides of the members of the said circular 15 casing. The said outer journal 27 projects for a suitable distance from the outer side of the worm-gear and is provided with a cross-pin 29. The operating-lever 30 has a hub or sleeve 31 at its inner end, which is adapted to 20 fit on the said outer projecting journal of the worm-gear and to turn thereon and is provided in opposite ends with notches 32 to engage the respective ends of the said cross-pin and with reversely-curved cams 33, which 25 serve by the partial rotary movement of the said lever first in one direction and then in the other direction to cause the ends of the cross-pin to be alternately engaged and disengaged by the said notches, so that the said 30 worm-gear by thus operating the said lever may be rotated by a step-by-step movement to raise or lower the vertically-movable bar. The axis of the worm-gear is inclined, as shown in Fig. 1, to bring the upper portion of the 35 frusto-conical face thereof into parallel relation with the opposing side of the vertically-movable rack-bar and cause the volute or worm flange of the gear to closely engage the teeth of said rack-bar.
- 40 Having thus described my invention, what I claim as new, and desire to secure by Letters Patent, is—
- 45 1. In a lifting-jack, the combination of a vertically-movable bar having rack-teeth, each of which is curved from end to end transversely of said rack-bar, a guiding and supporting element for the bar, a worm-gear hav-
- ing its bearings in said guiding and supporting element, said worm-gear being provided with a frusto-conical inner face opposed to the 50 toothed face of the rack-bar and having a volute or worm flange on said frusto-conical face flared outwardly, with its outer face substantially perpendicular to said frusto-conical face, the radius of the said flange being substantially equal to that of the curved teeth of the rack-bar, said flange successively engaging the opposing under sides of the teeth of the rack-bar, and means to rotate said worm-gear, substantially as described. 55
2. In a lifting-jack, in combination with a vertically-movable rack-bar, and a worm-gear engaging the same when said worm-gear is turned, a standard comprising two separable sections formed on their opposing sides with 60 a guide-opening for the reception of the lower lift of said rack-bar and with a casing for the reception of said worm-gear, the latter having journals projecting from its inner and outer sides, and the said casing being formed 65 in its inner and outer sides with bearings for the said journals, substantially as described. 70
3. In a lifting-jack, the combination of a standard, a vertically-movable rack-bar, and a revoluble worm-gear engaging said rack-bar, the latter and the said worm-gear being mounted in the said standard, and said worm-gear having an outwardly-projecting journal 75 provided with a cross-pin, and a lever having a hub to rotate on said projecting journal and 80 provided in its opposite ends with notches to engage said cross-pin, and reversely-curved cams to coact with said cross-pin to successively engage said notches therewith when said lever is reversely turned and thereby rotate said worm-gear by a step-by-step movement, substantially as described. 85

In testimony whereof I have hereunto set my hand in presence of two subscribing witnesses.

ERNEST WÜSTNER.
